UNITED STATES PATENT OFFICE.

WILLIAM E. OEHRL, OF PHILADELPHIA, PENNSYLVANIA, ASSIGNOR TO
OEHRL BROTHERS & CO., OF SAME PLACE.

DESIGN FOR A TASSEL.

SPECIFICATION forming part of Design No. 21,094, dated October 6, 1891.

Application filed September 10, 1891. Serial No. 405,326. Term of patent 7 years.

To all whom it may concern:

Be it known that I, WILLIAM E. OEHRL, a citizen of the United States, residing at Philadelphia, Philadelphia county, State of Pennsylvania, have invented and produced a new and original Design for Tassels, of which the following is a specification.

This design is intended more particularly for tassels to be used as curtain-shade pulls, although the design may be applied, generally, to ornamental tassels to be employed for various other purposes.

In the accompanying drawing is illustrated a tassel embodying my design.

15 The leading features of the design are the comparatively long and slender body of uniform diameter, with an open-work covering somewhat resembling netting, and a finishing-band formed of a multiplicity of loose loops interlaced to present a fluffy wave-like appearance, the outer face of the band being generally parallel with the body of the tassel.

20 A designates the tassel-body, provided at its lower end with a full round skirt B, while at the upper end it is rounded off and joined to the suspension-cord a, the body of the tassel being covered by an ornamental cord b, wound spirally thereon. This cord b is itself covered by a spirally-wound cord b', so that when

the cord b is wrapped upon the body of the 30 tassel, as shown, the adjacent parts of the cord b' intermesh and form an open-work covering resembling netting.

The finishing-band C is comparatively wide and located intermediate the upper end of the 35 tassel-body and the skirt, a considerable portion of the body extending above and below the band. The band is formed of a number of loose interlaced loops c, which give it a broken outer surface composed of rounded or 40 wave-like projections, the edges or upper and lower faces of the band being generally at a substantial right angle to the tassel-body, while the periphery or outer face d of the band is generally parallel with said body. 45

The tassel above described is highly ornamental, and may be easily produced at a comparatively small cost.

I claim—

The ornamental design for tassels, substantially as herein shown and described.

In testimony whereof I have signed my name to this specification in the presence of two subscribing witnesses.

WM. E. OEHRL.
